DESIGN FOR A LADY'S UNDERGARMENT OR THE LIKE

Doris Miller, New York, N. Y., assignor to Doris Miller, Inc., New York, N. Y., a corporation of
New York

Application February 27, 1942, Serial No. 106,005

Term of patent 3½ years

To all whom it may concern:

Be it known that I, Doris Miller, a citizen of the United States and a resident of New York, in the county of New York and State of New York, have invented a new, original, and ornamental Design for Lady's Undergarment or the like, as shown, of which the following is a specification, reference being had to the accompanying drawing, forming a part thereof.

I claim:

The ornamental design for a lady's undergarment or the like, as shown.

DORIS MILLER.
